UNITED STATES PATENT OFFICE.

DAVID J. HAUSS, OF CINCINNATI, OHIO.

DESIGN FOR A FRAME FOR DYNAMOS.

SPECIFICATION forming part of Design No. 18,099, dated February 21, 1888.

Application filed January 6, 1888. Serial No. 260,021. Term of patent 7 years.

To all whom it may concern:

Be it known that I, DAVID J. HAUSS, of Cincinnati, in the county of Hamilton and State of Ohio, have invented a new and useful Improvement in a Design for Dynamos, which design is fully set forth in the following specification and accompanying drawing, in which the accompanying figure represents a perspective view of the design.

This design consists in the configuration and shape of the several parts constituting the frame of the dynamo, as will now be set forth and explained, reference being had to the accompanying drawing, in which—

A represents the central upper part of one of the poles of the magnet, which has an upwardly-curved or convexed top, C; and B represents the central lower part of the opposite pole, which on its under surface, D, is concaved correspondingly or concentrically with the upwardly-curved top C. The standards F of the frame are placed at the ends and the

parts A centrally between them. The said standards are provided with side enlargements, G G. The tops H of the uprights are slightly arched to correspond with the convexity of the part A, and the uprights are also slightly inclined.

I claim—

In a dynamo, the design for the frame thereof, the same consisting of the central upper part, A, having its upper surface, C, upwardly curved or convexed, and its central lower part, B, having its under surface, D, correspondingly concaved, and the end pieces, F, having side enlargements, G G, and slightly inclined, substantially as herein set forth.

In testimony that I claim the foregoing I have hereunto set my hand, this 30th day of November, 1887, in the presence of witnesses. DAVID J. HAUSS.

Witnesses:

EDWARD BARTON,
R. S. MILLAR.
